UNITED STATES PATENT OFFICE.

THOMAS J. POTTINGER, OF GETHSEMANE, KENTUCKY.

CONSTRUCTION OF WHISKY-RACKS FOR BONDED WAREHOUSES.

SPECIFICATION forming part of Letters Patent No. 244,662, dated July 19, 1881.

Application filed March 1, 1881. (Model.)

To all whom it may concern:

Be it known that I, THOMAS J. POTTINGER, of Gethsemane, in the county of Nelson and State of Kentucky, have invented a new and useful Improvement in the Construction of Whisky-Racks for Bonded Warehouses, of which the following is a full, clear, and exact description.

The object of this invention is to reduce the cost of bonded warehouses for storage of whisky.

The revenue laws extending the bonding of whisky from one to three years make it necessary to increase the number or capacity of bonded warehouses, and it is desirable that the racks in such houses should combine great storage capacity with cheapness of construction. The most approved method of construction at present is to set up rows of upright timbers within the house, about three feet apart in one direction, and brace or hold them together with iron bolts and rods having nuts on each end, and to lay on these bolts and rods the stringers in one tier above another for supporting the barrels of whisky.

This invention consists of racks composed of a series of frames, each of which series is made of four stout upright timbers cross-channeled on one face and arranged side by side in pairs about three feet apart, each pair being tied together by two or more parallel timber or joist cross-ties, that are spiked or nailed one above another in the cross-channels, and have their ends extending on either side of the pair of uprights. These two pairs of upright timbers are fixed in a stout sill, and have a suitable cap or top plate parallel with the sill spiked on their tops, and thus form a frame, several of which, set parallel with and facing each other at suitable distances apart, support long stringers of joist that rest on the protruding ends of the cross-ties, and are spiked to the outer faces of the uprights, on which stringers the whisky-barrels are to be placed. A set or group of frames and stringers forms a rack, any desired number of which may be set up together, according to the size of the building.

The drawing represents a perspective view of a rack constructed on my improved plan, with barrels stored in position.

In the drawing, A represents a frame con-

sisting of upright timbers B B, cross-channeled on one face, as shown at a, at regular intervals. Said timbers B B are spiked on a suitable sill, F, and are further held by a cap, G, spiked on their tops by spikes c, as shown, and each pair of timbers B is held together and braced by the cross-ties D, about three feet long, that are fitted into the channels a, 60 and secured therein by spikes b. Said cross-ties D are made of wood, preferably of white oak, and serve not only as braces for the upright timbers B B, but also as supports for the stringers E, the ends of said cross-ties D 65 extending beyond the sides of the timbers B B far enough for the said stringers C to rest upon. The stringers E are preferably about eighteen feet long, or of any desired length, according to the size of the warehouse, and each stringer is supported at the center and ends by a cross-tie, D. The ends of said stringers E are also spiked, as shown at d, to the upright posts B B, whereby additional strength and stability are given to the whole rack. 70 Several of these frames A, together with suitable stringers, E, form a rack, and in this instance three of these frames A are included in a rack, as shown in the drawing. No rods nor bolts are used in the construction of these 75 racks, but the only fastenings are spikes or nails.

The whisky-barrels are supported in single tiers on the stringers E, as shown. A warehouse eighty-four feet long, forty-two feet wide, 85 and sixteen feet high, containing these racks, with a six-feet passage-way extending centrally from one end to the other, and on each side of this passage-way as many racks with eighteen-feet stringers as can be placed with 90 three-feet spaces between each rack, will hold about two thousand barrels of whisky, the said barrels resting in single rows on the stringers E, as shown at H.

A bonded warehouse with racks arranged 95 on this plan can be fitted up very quickly and cheaply. Each barrel is separately supported, and all are readily accessible.

I am aware that the several parts of a barrel-rack have been spiked or nailed together; 100 but

What I claim is—

1. A whisky-rack constructed substantially as herein shown and described, consisting of

transversely-channeled upright timbers B B, set in pairs or sills F, spiked or nailed top plates, G, cross-ties D D, in pairs, spiked or nailed in the channels of the timbers B B,

5 stringers E E, resting on the ends of the ties D D and nailed on the sides of timbers B B, all as set forth.

2. In the construction of a whisky-rack, the combination, with the transversely-channeled

upright pairs of timbers B B, and sills and 10 plates F G, of the spiked pairs of cross-ties D D and stringers E E, substantially as herein shown and described.

THOMAS JEFFERSON POTTINGER.
